Company, Inc., Altavista, Va., a corporation of Virginia

Application February 17, 1959, Serial No. 54,649

Term of patent 14 years

(Cl. D5—4)

The figure is a perspective view of a headboard for a bed embodying my design.

The surface of the back and right hand side of the headboard (not shown in the drawing) are plain and unornamented.

I claim:

The ornamental design for a headboard for a bed, as shown and described.
